Adams Corporation, Buffalo, N. Y.

Application February 28, 1941, Serial No. 381,160

12 Claims. (Cl. 141—7)

This invention relates to apparatus for treating articles with a fluid medium and more particularly to the washing of milk cans and covers in a milk receiving plant. In the washing of such cans heretofore, the cans have been moved along a selected path by step by step movements and, while in different stations along said path, subjected to fluid treatments for washing, rinsing, sterilizing, and drying of the same. It is desirable to control the streams of some of said fluids so that there will be no waste of the fluid while the cans are moving from one station to another and no delivery of a treating fluid to a particular station when no can and its cover or article is in that station. Heretofore, this control has been obtained by valves controlling such streams, and such valves have been opened by mechanism which is directly operated by the pressure obtained by camming aside a lever that is disposed in the path of travel of the cans or articles as they move into particular stations. To open such valves requires considerable pressure, and, consequently, considerable force must be exerted by the can or article on the lever or other mechanism which is operated thereby to open the valve. This pressure causes a substantial rubbing action on the cans or articles, which tends to wear off the finish thereof, and in the case of milk cans this pressure wears off the tinned surface so as to expose the metal there-beneath. Such worn surfaces then rust or corrode and become unsightly and in time weaken the cans or cause leakage through the walls.

An object of this invention is to provide improved means for controlling the fluids delivered to the cans or articles moving along a selected path, with which the wear on the articles or cans is very greatly reduced, which will be relatively simple, compact, durable and inexpensive, and which will not greatly increase the cost of the apparatus.

Another object of the invention is to provide improved means for controlling a fluid delivered to articles passing along a selected path under the control of the articles in said path, with which the actual operation of the valves is obtained from a suitable source of power and not from the pressure by any article as the article passes along its path of travel, with which the operation of the valve by the source of power is selectively controlled by the presence and absence of an article from a selected station in said path, as said articles move in succession along said path, and with which wear on the articles, because of such control, will be a minimum.

Another object of the invention is to provide simple and effective means for controlling the delivery of a fluid to articles such as milk cans, as the articles move in succession along a selected path, with which the valves will be power operated and such operation made automatically responsive to the presence or absence of a can or article in any selected position in said path, with which unnecessary wear of said articles while passing along said pathway will be avoided, with which the operation of the valves will occur in timed relation to the movement of the articles along said path, with which the time of application of the treating fluid can be exactly governed by the design of the operating mechanism, which will require a minimum of operating parts, and which will be relatively simple, quiet, compact and inexpensive.

Other objects and advantages will be apparent from the following description of an embodiment of the invention in a typical can washing machine, and the novel features will be particularly pointed out hereinafter in connection with the appended claims.

In the drawings:

Fig. 1 is a side elevation of a portion of a milk can and cover washing machine, in which the delivery of treating fluid to the cans and covers in certain of the treating stations is controlled by valves, and the valves are in turn controlled by the presence or absence of cans in the stations to which fluid is delivered and in which the valves are controlled in accordance with this invention;

Fig. 1a is an elevation of the connections between certain details of the same;

Fig. 2 is a sectional plan of a portion of the same, illustrating the manner in which the control of the valves is accomplished in timed relation to the movement of the cans through the treating stations;

Fig. 3 is a sectional plan, on a larger scale, through a portion of the washer at one of the treating stations to illustrate the manner in which the valves are controlled by the cans as the cans move into a treating station, the cans in this view being shown at intermediate points between stations;

Fig. 4 is a similar view after the interponent has been set, by the presence of a can in a selected station, ready to cause an operation of the valve by the source of power, but before the operation of the valve has started;

Fig. 5 is a view similar to Fig. 4 showing the position of the parts occupied after the valve has been opened by the source of power and with cer-

tain of the parts in section to show more clearly some of the details of the parts;

Fig. 6 is a transverse, sectional elevation through the valve controlling mechanism, the section being taken approximately along the line 6—6 of Fig. 3;

Fig. 7 is a side elevation of the mechanism shown in Fig. 3, with the valve in section to show interior details thereof;

Fig. 8 is a sectional elevation similar to Fig. 6, but showing the change in the position of the interponent after it has been shifted into effective position to cause an operation of the valve; and

Fig. 9 is a side elevation of the mechanism of Fig. 8 while the parts are in that same position.

In the illustrated embodiment of the invention, the articles selected to be treated with a fluid medium are milk cans, and the treatment includes the washing, rinsing, sterilizing and drying of the cans and their covers as they pass through the machine along a selected path. Machines of this type are common in the art, and the drawings illustrate generally a typical example of such a can and cover washing machine to which this invention has advantageously been applied. In the drawings, many parts of the washing machine not directly modified by this invention, have been omitted in order not to obscure details of the application of this invention to a machine of that type.

A typical can washing machine of this type includes a housing 10 having therein from end to end, rails 11 on which the cans are supported and along which they slide while in an inverted position, and also a rail 12 which extends generally from end to end of the housing, and on the upper edge of which the covers are rolled successively through treating stations in proximity to the cans to which those covers respectively belong. Such rails 12 commonly have notches 13 into which the covers roll, and which serve to yieldingly hold the covers in the different treating stations and prevent over-running of the covers as they are propelled along the rail 12. The covers are pushed along the rail 12 by dogs 14 which are pivoted to a dog bar 15 at spaced intervals therealong, the dogs being over-weighted at one end so as to normally assume generally upright or upwardly inclined positions as shown in Fig. 1. When the dog bar 15 is advanced, the dogs 14 will engage the necks of the covers and push or roll the covers along, it being understood that during the retraction of the dog bar 15, the upstanding end of each dog will be cammed downwardly and ride under the neck of any cover which has been pushed into its path by the next adjacent dog. Thus, when the dog bar 15 is moved to the right in Fig. 1, the dogs 14 thereon will push any covers against which they may engage to the right from one notch 13 to another, each notch representing one treating station.

During the movement of the dog bar 15 to the left, or retraction, the dogs 14 will return to their stations to the left of the notches 13. If a cover has been pushed into any station, the dog passing that station in its return will be cammed downwardly at its upstanding end through its engagement with that cover, and after the dog passes the cover the dog will automatically return to its upstanding position ready to push the cover in that station forward at the next movement of the dog bar 15 to the right in Fig. 1. Similarly, the cans are pushed along the rails 11, which form a track, by pairs of dogs 16 which are pivoted at

17 to dog bars 18 which are disposed along side the rails 11 and which are shifted endwise in reciprocating movements in a manner which will be described presently.

The dogs 16 are also each over-weighted at one end so as to normally present upstanding noses, which project above the plane of the upper edges of the rails 11 sufficiently to engage the outer edge of the lower or open end of the can which is riding on the rails 11 at opposite sides of the center thereof, so that when the dog bars 18 are shifted to the right in Figs. 1, 2 and 3, each pair of dogs 16 will shift any can immediately in front thereof to the right from one station to another, which stations are determined by the normal positions occupied by the cans after being pushed by the dogs 16 during their travel or advance to the right. During the movement of the dog bars 18 to the left, which is the return movement, the upstanding noses of the dogs 16 will be cammed downwardly by any cans now engaged thereby that have just been moved forwardly to new stations, and upon reaching retracted positions will again return to upstanding positions as shown in Fig. 1, ready to again push forward, or to the right in Figs. 1 to 3, from station to station, all cans which are in the treating stations.

The dog bars 15 and 18 are reciprocated endwise in a selected cycle of operation in any suitable manner. In the particular example illustrated, the operating power for the dog bars is obtained from a shaft 19 which carries a gear 20 driven by a gear 21 and suitable motor not shown, it being understood that the shaft 19 may rotate continuously. A cam 22 is fixed on the shaft 19 or to the gear 20 so as to rotate with the gear 20, and this cam 22 has, in a face thereof, a cam groove 23 (Fig. 1) which varies in its radial distance from the axis of rotation of the shaft 19 in a manner which is predetermined by the particular desired cycle of movement of the dog bars. A roller or cam follower 24 runs in the groove 23 and is rotatably carried by a pin 25 on a lever 26, which is pivoted at 27 to a base bearing 28. The lever 26 swings generally in the direction of endwise movement of the dog bars, and it is connected by a pin 29 to one end of a link 30 (Figs. 1a and 2), the other end of which is connected by a horizontal pivot 31 to a bearing king pin 32 which has a depending shank 33 rotatably connected to an arm 34, which in turn is fixed on an upright shaft 35.

The shaft 35 extends generally from the level of the dog bar 15 to the level of the dog bars 18. The dog bars 18 are connected together so as to operate in unison, and one of these dog bars is pivotally connected by a pin 36 to one end of a link 37 which is connected at its other end by a suitable pivot pin to the free end of the arm 34. An arm 38 is fixed upon a shaft 35 at its upper end, and the free end of that arm is pivotally connected by a pin 39 to one end of a link 40, the other end of which is pivotally connected by a pin 41 to the cover dog bar 15. Thus, when the shaft 35 is rocked, it will act through its arms 34 and 38 to cause simultaneous and corresponding reciprocations of the dog bars 15 and 18 and thus propel the covers and cans in unison from station to station. Inasmuch as the connection from link 30 to arm 34 moves through an arc during operation of the shaft 35, the link 30 may also be provided with a hinged joint 42 which allows generally horizontal toggle movement of the link 30. It will be understood that this operation of the dog bars from the cam 22 is old in the art,

and is not, per se, part of the invention, but is illustrated and described sufficiently to explain its operation in timed relation to the valve controlling mechanism.

It will be observed that as the shaft 19 rotates continuously in the same direction, it will cause reciprocations of the dog bars 15 and 18 and while the follower 24 is running in the circular arc portion of the groove 23 farthest from and concentric to the shaft 19, the dog bars will be in retracted positions and quiet for a substantial interval of time sufficient to enable treating operations of the cans and covers in the different stations through which they travel.

Also fixed on the shaft 19 (Figs. 1 and 2) is another cam 43, and this cam at its peripheral edge, engages with a cam follower or roller 44 rotatably mounted on an end of a bell crank lever 45 which is pivoted at 46 to an upstanding bearing element 47. The other arm of the bell crank 45 carries a weight 48 which is secured in adjusted positions by a set screw 48a and may be adjusted to different distances from pivot 46 to exert an adjustable turning force on the bell crank lever and urge the roller 44 into following contact with the periphery of the cam 43. The bell crank 45 has an upstanding portion 49 which is pivotally connected at 50 to one end of a rod 51. The pin 50 has sufficient play in the upstanding end 49 of the bell crank lever 45 so that the end of rod 51 may move in a strictly endwise direction, while the opening in the end 49 of the lever 45 in which pin 50 engages moves through a small arc. This play may be obtained by elongating the opening in the lever end 49 in a direction toward the pivot 46 as is well known in mechanical movements.

The rod 51 extends in a direction generally parallel to the direction of movement of the dog bars 18, and is supported for such endwise sliding movement at a plurality of points by bearings 52 (Fig. 2). It will be noted from Fig. 1 that while the follower 24 is running in the portion of groove 23 which is concentric to the shaft 19, the cam 43 will rock the bell crank 45 in a manner to shift the rod 51 to the right, and hold it in that shifted position as the roller 44 rides along a substantial zone of cam 43 which is concentric to the shaft 19. The roller 44 is released for movement towards the shaft 19 about the zone where the dog bars begin their advance. The weight 48 shifts the roller 44 toward the shaft 19 and in doing so shifts the rod 51 back to the left and holds it in that retracted position throughout the remaining period of the rotation, during which period of rest for rod 51 the dog bars are shifted to advance the cans and covers from station to station.

In their travel through the machine, and while in different stations, the cans and covers are subjected to different cleaning treatments in which they are usually first rinsed, then washed with a suitable detergent, rinsed, sterilized and dried. Certain of these treatments, such as some of the rinsing treatments, utilize steam and fresh water for example, and it would be an unnecessary waste of such water and steam to deliver the same at the respective stations when milk cans and covers are not in those stations, and the splashing of such rinse water in the interior of the machine when no can and cover are in positions to be treated thereby might result in some unnecessary dilution of the washing solution. Accordingly, at any of these stations where delivery of a liquid is not desired whenever a can

and its cover are not in their respective stations to receive the treatment, a control is provided for that liquid in the nature of a valve which is opened only when the can and its cover are in those stations. Inasmuch as the control is the same at each of the stations, the control for only two of such stations has been shown, but obviously this control can be similarly applied to any of the stations.

- 10 In the illustrated example of the invention, a valve 53 controls the delivery of the intermediate pump rinse water to cans in station A and to covers for the same cans that are in station B. Similarly a valve 54 controls delivery of sterile 15 rinse water to any cans in station C and to the corresponding covers in station D. As valves 53 and 54 are normally urged into closed condition in any suitable manner, a typical valve for that purpose is shown in Fig. 7, and since all of the 20 valves are the same, this particular valve in Fig. 7 is designated as valve 53. In this type of valve, a valve element 55 is urged against a seat within the valve by a spring 56, and the valve element 55 has an operating stem 57 which extends outwardly of the valve housing, so that whenever the outer end of the valve stem 57 is depressed against the action of spring 56, the valve will be 25 opened to pass fluid through the pipe 58 from the pump 59.
- 30 After passing the valve 53, the pipe 58 branches, one branch 58a passing beneath any can in station A and directing liquid upwardly into any can that is thereover. The other branch 58b passes upwardly to station B for the corresponding cover 35 of that can, and there terminates in branches which deliver several streams of rinsing water against the cover as usual in this type of machine. Heretofore, in some prior devices the valve stems 57 have been operated against the 40 action of spring 56 by a lever disposed in the path of the can at a station, so that as any can moved into that station it cammed the lever aside and in doing so depressed the stem 57 and opened the valve. The pressure required to so open a 45 valve caused considerable wear on the surface of the can where engaged by the lever, and in accordance with this invention, this wear has been largely eliminated by having the can, as it moves 50 into the station, merely control the activity of the valve and not furnish the actual valve operating force or pressure.

Referring particularly to Figs. 5 to 9, one form of this control is illustrated. A sleeve or transmission element 60 is mounted on the rod 51 for sliding movement therealong in a zone adjacent the valve 53. The sleeve 60 has an arm 60a which abuts against the outer, free end of the valve stem 57 of valve 53. The face of the arm 60a which engages stem 57 is provided with an internal recess 61 (Fig. 5) which loosely fits over the end of stem 57. This engagement between the stem 57 and the arm 60a prevents rotation of sleeve 60 on rod 51, and since the stem 57 is substantially parallel to the rod 51, endwise movement of sleeve 60 with rod 51 will cause a depression of the valve stem 57. The sleeve 60 is also provided with an arm 60b, and a rod 62 is threaded through the arm 60b adjacent the free end of the latter in a direction parallel to the 65 rod 51. An interponent or plate 63 is pivotally mounted on the rod 62 and is confined against the arm 60b by a nut 64 and washer 65, the nut 64 being threaded upon the rod 62. By the word 70 interponent is meant a member which may be selectively interposed between two other parts to

transmit motion between them, and removed from between them to interrupt such transmission of movement. The interponent or plate 63 is free to oscillate about the rod 62 and is provided with two slots 66 and 67, the slot 66 extending from a point adjacent the rod 62 to progressively increasing radial distances therefrom as shown clearly in Figs. 6 and 8. An arm 68 (Fig. 9) extends from a sleeve 69 on the lower end of a shaft 70 to which it is secured, through the slot 66 in a direction generally parallel to the rod 51, so that when the arm 68 is rocked with the shaft 70 it will act as a cam follower in the slot 66 of the interponent or plate 63 and will rock the latter about the rod 62. The shaft 70 is rotatably mounted in the bearing 71 and also carries an arm 72 which extends into the path of travel of the lower peripheral edge of the open end of the inverted can as shown in Fig. 3, so that as any can moves into the station A, its lower edge, which is the open edge of the mouth of the inverted can, will engage the arm 72 and cam it into the position shown in Fig. 4.

When the arm 72 is rocked in this manner it shifts the arm 68 from the position shown in Fig. 3 to the position shown in Fig. 4, and in its movement between these positions, arm 68 shifts the interponent or plate 63 from the normal or inactive position shown in Figs. 3, 6, and 7 into the active position shown in Figs. 4, 5, 8 and 9. The slot 67 opens through an edge of the plate as shown in Fig. 6 and is arcuate, with its center of curvature at the rod 62, and a radius equal to the distance from rod 62 to rod 51, so that when the interponent plate 63 is rocked from the position shown in Fig. 6 to the position shown in Fig. 8, the slot 67 will clear the rod 51, it being understood that the width of the slot 67 is greater than the diameter of the rod 51. The end portion of the plate 63 adjacent to the slot 67 is substantially weighted, so that when the interponent is in said active position, the forces of gravity urge it to rotate and to rock said end portion downwardly into the position illustrated in Fig. 6. The rod 51 is provided with an abutment or shoulder 73 which moves with the rod 51, and this abutment is advantageously secured by providing a collar 74 on the rod 51 for movement with the latter.

A set screw 75 serves to secure the collar 74 in any of the different positions into which it may be adjusted along the rod 51. The collar 74 is adjusted into such a position that when the rod 51 is at its left hand limit of movement in Fig. 1, it will be disposed in substantial distance from the adjacent end face of the sleeve 60, and when at its right hand limit of movement with the rod 51 will occupy the position shown in dash lines in Fig. 3. It will be observed that when the collar 74 moves with the rod 51 in this manner, it will stop just short of engaging and moving the sleeve 60 and there will be no depression of valve stem 57 of the valve 53. If the plate or interponent 63 is shifted into the position shown in Fig. 8 in which the slot 67 straddles the rod 51, then when the collar 74 moves from the full line position to the dash line position in Fig. 3, it will engage the plate 63 and move it and the sleeve 60 endwise with the rod 51 to the right, as shown by the full line arrow in Fig. 3. This causes a depression of the valve stem 57 and an opening of valve 53 to cause the delivery of a rinsing liquid to a can and cover in stations A and B.

During this movement of sleeve 60 with the rod 51, the plate 63 is free to ride along the arm 68 which shifted it into the active position shown in

Fig. 8 and holds it in that position. At the end of a cycle of movement of the rod 51, the cans and covers will be advanced, and as the can in station A moves forwardly, it will release the arm 72, whereupon the interponent or plate 63 by reason of its being heavier and weighted at the end which straddles the rod 51, will fall and through the slot 66 will rock the arm 68, shaft 70 and arm 72 back into the path of any other approaching can, which position of arm 72 is shown in Fig. 3. From this it will be observed that the valve will be opened while the rod 51 is in its right hand limit of movement in Figs. 1, 2, and 3 and a can is in station A, which usually will be throughout substantially all of the period while the can is stationary in station A.

If no can is in station A, the interponent 63 will, of course, be in its inactive position shown in Fig. 6, and the valve stem 57 of the valve 53 will remain inactive when the rod 51 moves to the right in Fig. 3. The same type of control is provided for the valve 54, and for that reason the corresponding parts for operating the valve 54 are given the same reference characters as those for operating valve 53.

It will be observed that the rod 62 is adjustable in directions lengthwise thereof, and that one end thereof is adjacent to and aligned with the sleeve 69, so that movement of the rod 62 and sleeve 60 lengthwise of the rod 51, on which sleeve 60 is loose, and to the left in Figs. 5 and 7, may be selectively limited by abutment of the rod 62 against sleeve 69. The rod 62 is adjusted to limit excessive movements of the sleeve 60 which might enable the sleeve to slip off of the valve stem 57 and become disconnected therefrom.

From the foregoing it will be observed that the only pressure exerted by the arm 72 on the can edge which cams it aside is that relatively slight pressure exerted by the weighted interponent 63, which is urged by gravity to rotate into the inactive position shown in Fig. 6. The only pressure transmitted through the can is that sufficient to shift the interponent 63 into the active position which is relatively small, and the work of operating the valve is performed entirely by the rod 51 under operation by the cam 43. Because of this, the wear on the cans which tends to destroy the tinning on the engaged surface thereof will be very slight, and the life of the cans very greatly increased.

The valve 54, in the illustrated example, controls the delivery of sterile rinse water received from a suitable source, through pipe 54a, and this pipe beyond the valve 54 branches, one branch 54b going to a position beneath any can in station C and the other branch 54c delivering rinse water to the covers in station D.

It is believed that the operation of the apparatus will be clear from the foregoing description, and it will be understood that various changes in the details and arrangement of parts, which have been herein described and illustrated in order to explain the nature of the invention, may be made by those skilled in the art within the principle and scope of the invention as expressed in the appended claims.

We claim as our invention:

1. In a machine for washing articles such as milk cans, a track along which the cans are moved in inverted positions, means including an operating cam for moving said cans through selected treating stations in succession along said track in step by step movements with substantial

intervals of rest in said stations between movements, a rod extending in a direction approximately parallel to the track and mounted for endwise movement, an abutment on said rod, means operated in timed relation to said cam for moving said rod endwise in one direction and for holding it so moved during a substantial portion of each of said intervals, a valve having an operating element urged continuously and yieldingly into closed position, a sleeve slideable freely and endwise on said rod adjacent said abutment and operable on said element to force it into open position when said sleeve moves in said one direction endwise of said rod, an interponent mounted on said sleeve for movement thereon into and out of a position in the path of said abutment as said rod moves endwise in said one direction so as to be engaged and moved by said abutment and thereby cause operation of said valve element, the path of travel of said abutment terminating before the abutment normally causes material movement of the valve element when the interponent is out of the path of movement of the abutment, means responsive to the presence of a can in a selected one of said stations for causing movement of said interponent into the path of movement of said abutment automatically, and means controlled by said valve for directing a treating fluid towards said can then in said selected station.

2. In a machine for washing articles such as milk cans, a track along which the cans are moved in inverted positions, means including an operating cam for moving said cans through selected treating stations in succession along said track in step by step movements with substantial intervals of rest in said stations between movements, a rod extending in a direction approximately parallel to the track and mounted for endwise movement, an abutment on said rod, means operated in timed relation to said cam for moving said rod endwise in one direction and for holding it so moved during a substantial portion of each of said intervals, a valve having an operating element urged continuously and yieldingly into closed position, a sleeve slideable freely and endwise on said rod adjacent said abutment and operable on said element to force it into open position when said sleeve moves in said one direction endwise of said rod, an interponent mounted on said sleeve for movement thereon into and out of a position in the path of said abutment as said rod moves endwise in said one direction so as to be engaged and moved by said abutment and thereby cause operation of said valve element, the path of travel of said abutment terminating before the abutment normally causes material movement of the valve element when the interponent is out of the path of movement of the abutment, a lever having an arm disposed within the path of travel of said cans as they move into said one of said stations and operable by any can moving into said one of said stations, a rod member extending generally in a direction parallel to the direction

- 5 of endwise movement of said rod rocked by said lever, said interponent having a slot which from end to end progresses to increasingly greater radial distances from the pivotal axis of the interponent and through which said rod member loosely extends, whereby rocking of said lever by a can will shift said interponent into a position to transmit movement from said abutment to said sleeve and through the sleeve to said valve, and said interponent may slide along said rod member without disengagement therefrom while said sleeve and interponent are moved with said rod.
- 10 4. An improved device for treating articles with a fluid medium, which comprises means for conveying the articles along a selected path, a rod mounted generally parallel to said path and adjacent thereto, means for shifting said rod back and forth endwise, a valve having a valve stem shiftable endwise between open and closed positions of the valve, means yieldingly urging said valve stem into closed position, a sleeve loosely slideable on said rod and engageable with the end of said valve element to shift said valve element against the action of said urging means into open position, an abutment on said rod adjacent said sleeve, an interponent mounted on said sleeve for movement into and out of a position in which it is disposed between said abutment and sleeve, means operable by an article passing along said path for shifting said interponent into said position, said abutment being positioned on said rod to normally stop before moving said sleeve but to engage said interponent before completing its movement toward the sleeve when the interponent is in said position, and operable through
- 15 5 the interponent when continuing its movement in the same direction for shifting said sleeve in a direction to cause a movement of said valve element into open position, and means controlled by said valve for directing a fluid to an article in said path.
- 20 6. In a machine for washing articles such as milk cans, a track along which the cans are moved in inverted positions, means including an operat-
- 25 7. In a machine for washing articles such as milk cans, a track along which the cans are moved in inverted positions, means including an operat-
- 30 8. In a machine for washing articles such as milk cans, a track along which the cans are moved in inverted positions, means including an operat-
- 35 9. In a machine for washing articles such as milk cans, a track along which the cans are moved in inverted positions, means including an operat-
- 40 10. In a machine for washing articles such as milk cans, a track along which the cans are moved in inverted positions, means including an operat-
- 45 11. In a machine for washing articles such as milk cans, a track along which the cans are moved in inverted positions, means including an operat-
- 50 12. In a machine for washing articles such as milk cans, a track along which the cans are moved in inverted positions, means including an operat-
- 55 13. In a machine for washing articles such as milk cans, a track along which the cans are moved in inverted positions, means including an operat-
- 60 14. In a machine for washing articles such as milk cans, a track along which the cans are moved in inverted positions, means including an operat-
- 65 15. In a machine for washing articles such as milk cans, a track along which the cans are moved in inverted positions, means including an operat-
- 70 16. In a machine for washing articles such as milk cans, a track along which the cans are moved in inverted positions, means including an operat-
- 75 17. In a machine for washing articles such as milk cans, a track along which the cans are moved in inverted positions, means including an operat-

5. An improved device for treating articles with a fluid medium, which comprises means for conveying the articles along a selected path, a rod mounted generally parallel to said path and adjacent thereto, means for shifting said rod back and forth endwise, a valve having a valve stem shiftable endwise between open and closed positions of the valve, means yieldingly urging said valve stem into closed position, a sleeve loosely slidable on said rod and engageable with the end of said valve element to shift said valve element against the action of said urging means into open position, an abutment on said rod adjacent said sleeve, an interponent plate pivoted on said sleeve for movement in a direction crosswise of the direction of movement of said rod into a position between said abutment and said sleeve, said plate having a slot from face to face and which from end to end progresses to increasingly greater radial distances from the pivotal axis of said plate, an arm extending generally parallel to said rod and through said slot, means operable by an article moving along said path for moving said arm in a direction to carry its portion within the slot toward said rod so as to rock said plate into a position between said abutment and said sleeve, said arm having a length sufficient to remain in said slot as said plate moves with said sleeve under actuation of said abutment, and means controlled by said valve for delivering a treating fluid to one of said articles while in said path.

6. An improved device for treating milk cans and the like with a fluid medium, which comprises means for conveying the cans in succession through a treating station with a substantial interval of rest in said station, means for delivering a treating fluid to said cans while approximately in said station, means for controlling the delivery of said fluid by said directing means and having an operating element through operation of which the delivery is stopped or permitted, a rod extending generally parallel to the direction of travel of said cans through said station, means mounting said rod for endwise reciprocation, means for reciprocating said rod in coordinated relation to the movement of said cans into and out of said station, a sleeve mounted on and sliding freely along said rod, and having one portion engaging said operating element to operate it and cause delivery of fluid to said station, a collar fixed on said rod in a position to approach closely to and recede from said sleeve without moving said sleeve during reciprocations of said rod, a member pivoted on said sleeve and movable thereon into and out of a position across the end of said sleeve to form an extension of said sleeve when across its end, said member having a thickness sufficient to be engaged by said collar and to transmit motion from it to said sleeve when said member is across the end of said sleeve and said collar approaches said sleeve, and to clear said collar when moved from across the end of said sleeve, and means disposed for operation by a can in said station, for positioning said member across the end of said sleeve while a can is in said station, whereby fluid will be delivered only while a can is approximately in said station.

7. An improved device for treating articles with a fluid medium, which comprises means for conveying the articles in succession through a treating station with a substantial interval of rest in said station, means for directing a fluid stream against said articles while in said sta-

tion, means for controlling said fluid stream and having an operating element through which delivery of fluid is controlled, a power operated member operable back and forth in timed relation to the advancement of said articles into said station, a transmission element slidable freely upon said member and engageable with and operating said element, a plate pivoted on said transmission element to swing crosswise thereof, said member having an abutment near said transmission element but stopping short of engagement with said transmission element, but engageable with said plate to move it and said transmission element and operating element when said plate is swung into the path of said abutment, and means automatically responsive to the presence of an article in said station for shifting said plate into the path of said abutment, whereby the power necessary to operate said element and cause a delivery of fluid will be supplied by said power operated member.

8. An improved device for treating articles with a fluid medium, which comprises means for conveying the articles in succession through a treating station with a substantial interval of rest in said station, means for directing a fluid stream against said articles while in said station, means for controlling said fluid stream and having an operating element through which delivery of fluid is controlled, a power operated member operable back and forth in timed relation to the advancement of said articles into said station, an interponent mounted to move freely in the direction of movement of said member but shiftable crosswise of said direction into and out of a position in which it transmits motion from said power operated member to said operating element to cause delivery of fluid to said articles in said station, a control member disposed in the path of movement of said articles and pushed generally horizontally and crosswise of said path by each article moving into and through said station, once only for each article passing said station, a rod connected to and moving with said control member, extending generally in the direction of movement of said power operated member, said interponent having a cam portion slidably engaging with said rod by which movement of said rod will shift said interponent into and out of its said position, and said interponent may slide along said rod without movement out of its said position, as said interponent moves with said power-operated member.

9. An improved device for treating articles such as open milk cans, with a fluid medium, which comprises means for conveying the cans in inverted positions in succession through a treating station with a substantial interval of rest in said station, a control member urged into the path of travel of the edge of the open mouth of each can as it moves through said station so as to be pushed aside horizontally by said edge, said member having a rod extending therefrom, a power-operated element reciprocating in a direction generally parallel to said rod during said rest, means for delivering fluid to any can which is in said treating station, a valve controlling said means, means for operating said valve, an interponent plate disposed with its faces crosswise of said rod, mounted for one movement in a direction crosswise of said rod into and out of a position in which it causes operation therethrough of said valve operating means from said power operated element, and

also free to move with said element in said direction, said plate having a cam slot therein through which said rod extends, said rod when rocked with said member by movement of a can into said station, in turn shifting said plate into said position to transmit motion from said element to said valve operating means to open said valve, said rod having relative endwise movement in said slot of said plate as said plate moves with said element.

10. An improved device for treating articles with a fluid medium, which comprises means for conveying the articles in succession through a treating station, with a substantial interval of rest in said station, means for directing a fluid stream against said articles while in said station, means for controlling said stream and having an operating element movable back and forth, a power operated member also movable back and forth in timed relation to the advancement of said articles through said station and in a direction parallel to the movement of said element, said member having an abutment, a sleeve slidably mounted on said member and engageable with and operating said element in a direction in which it causes delivery of fluid to an article in said station, the movement of said abutment toward said sleeve being insufficient to move said sleeve and element and cause delivery of said stream to any article in said station, a plate mounted on said sleeve for movement between an inactive position in which it is out of the path of said abutment, and an active position in which it is between said abutment and said sleeve, said plate being of such thickness that when in said active position it will be engaged and moved by said abutment before said abutment completes its movement toward said sleeve, and will transmit movement from said abutment to said sleeve and element sufficiently to cause delivery of fluid to any article in said station, and means rendered effective by the presence of an article in said station for shifting said plate into said active position.

11. An improved device for treating articles with a fluid medium, which comprises means for conveying the articles in succession through a treating station, with a substantial interval of rest in said station, means for directing a fluid stream against said articles while in said station, means for controlling said stream and having an operating element disposed for movement back and forth in a direction parallel to the direction of movement of said articles, a rod extending parallel to said direction of movement of said articles and of said element means for reciprocating said rod endwise in timed engagement to the movement of said articles, said rod having an abutment thereon, a sleeve mounted on said rod for sliding movement therealong and having a portion engageable with said element

to move said element in one direction, means yieldingly urging said element in the other direction, said abutment in its movement in one direction approaching but not engaging said sleeve, a plate mounted on said sleeve for movement in a direction crosswise of said rod from an inactive position in which it clears said abutment to an active position in which it lies in the path of said abutment and is engaged and operated by said abutment to transmit the movement of said abutment to said sleeve sufficiently to cause a full operation of said element, and means responsive to the presence of an article in said station for camming said plate into said active position.

12. An improved device for treating articles with a fluid medium, which comprises means for conveying the articles in succession through a treating station, with a substantial interval of rest in said station, means for directing a fluid stream against said articles while in said station, means for controlling said stream and having an operating element disposed for movement back and forth in a direction parallel to the direction of movement of said articles, a rod extending parallel to said direction of movement of said articles and of said element means for reciprocating said rod endwise in timed engagement to the movement of said articles, said rod having an abutment thereon, a sleeve mounted on said rod for sliding movement therealong and having a portion engageable with said element to move said element in one direction, means yieldingly urging said element in the other direction, said abutment in its movement in one direction approaching but not engaging said sleeve, a plate mounted on said sleeve for movement in a direction crosswise of said rod from an inactive position in which it clears said abutment to an active position in which it lies in the path of said abutment and is engaged and operated by said abutment to transmit the movement of said abutment to said sleeve sufficiently to cause a full operation of said element, the mounting of said plate on said sleeve being a pivotal mounting and said plate having a slot therein from face to face, and progressing from one end which is a selected distance from the pivotal mounting of the plate in a direction to be at progressively greater radial distances from said pivotal mounting as the slot progresses from said one end, a shaft mounted for oscillation about an axis at right angles to, but offset from the axis of said rod, and having one arm extending through said slot and a second arm in the path of any article moving into said station, whereby the movement of an article into said station will rock said shaft and through it said plate into its said active position.
